CLAIM

The ornamental design for a GPS apparatus holder, as shown and described.

DESCRIPTION

The GPS apparatus holder mounted on a support device is used particularly for supporting GPS apparatus of different sizes in a position convenient for the user such an apparatus.

FIG. 1 is a perspective front view of a GPS apparatus holder, FIG. 2 is a perspective top view of the GPS apparatus holder shown in FIG. 1,

FIG. 3 is a perspective left side view of the GPS apparatus holder shown in FIG. 2,

FIG. 4 is a perspective right side view of the GPS apparatus holder shown in FIG. 2,

FIG. 5 is a perspective bottom view of the GPS apparatus holder shown in FIG. 1; and,

FIG. 6 is rear view of the GPS apparatus holder shown in FIG. 1.
